UNITED STATES PATENT OFFICE.

BYRON B. HAVENS, OF RUSHVILLE, NEW YORK.

WASH-BOARD.

SPECIFICATION forming part of Letters Patent No. 341,236, dated May 4, 1886.

Application filed November 5, 1885. Serial No. 181,956. (No model.)

To all whom it may concern:

Be it known that I, BYRON B. HAVENS, a citizen of the United States of America, residing at Rushville, in the county of Yates and State of New York, have invented certain new and useful Improvements in Wash-Boards; and I do hereby declare the following to be a full, clear, and exact description of the invention, such as will enable others skilled in the art to which it appertains to make and use the same.

The object of this improvement is a cheaply-constructed and efficient wash-board having a metal rubbing-surface composed of distinct parts of twisted wire and a skeleton frame, all so constructed and arranged that they will be interchangeable, in order that they may be detached and replaced by new parts should they become disqualified by wear or other causes. These results are attained by the mechanism illustrated in the drawings here-with filed as a part hereof, in which the same letters of reference denote the same parts in the different views.

Figure 1 is a perspective representation of a wash-board embodying the features of my improvement. Fig. 2 is a detail. Fig. 3 is a transverse section taken on the line $x-x$ of Fig. 1.

A, A', B , and C is a skeleton frame of which the outer parts, A, A' , form the legs or supports. A', B , and C are transverse braces.

The parts A, A' are suitably slotted for the reception of the ends of the parts B, C , which may be additionally secured to the parts A, A' by any suitable means.

The legs or supports A are provided with slots a , for the reception of the ends of the twisted wires D , which form the rubbing-surface of the wash-board, and which are provided at their ends with eyes, as fully shown at d in Fig. 2. These eyes d are inserted into the slots a of the parts A, A' , and secured in position by means of screws E , which enter the parts A in the order shown, and by passing through the eyes d into the opposite side of the frame-pieces not only secure the connection of the parts D , but also strengthen the parts A .

By removing the screws E the wires D may be removed and applied to a new frame; or either of them may be removed and replaced by other parts when disqualified by wear or other causes.

Having explained the features of my improvement, what I claim as new, and desire to secure by Letters Patent, is—

A wash-board having a rubbing-surface composed of a series of distinct interchangeable twisted wires having eyes at their ends for securing the same to the supporting-frame independently of each other, substantially as specified, for the purpose set forth.

In testimony whereof I affix my signature in presence of two witnesses.

BYRON B. HAVENS.
